(57) **CLAIM**

The ornamental design for a total air temperature probe, as shown and described.

DESCRIPTION

FIG. 1 is a perspective view as seen from the front, side and top of a first embodiment of a total air temperature probe of the present invention;

FIG. 2 is a top plan view of the total air temperature probe of FIG. 1;

FIG. 3 is a bottom plan view of the total air temperature probe of FIG. 1;

FIG. 4 is a front elevational view of the total air temperature probe of FIG. 1;

FIG. 5 is a rear elevational view of the total air temperature probe of FIG. 1;

FIG. 6 is a right side view of the total air temperature probe of FIG. 1; and,

FIG. 7 is a left side view of the total air temperature probe of FIG. 1.

The broken line showing of a flange and attached electronic housing are included for the purpose of illustrating non-claimed subject matter and forms no part of the claimed design.

1 Claim, 4 Drawing Sheets
